UNITED STATES PATENT OFFICE.

HORATIO SWEETSER, OF NEW YORK, N. Y., ASSIGNOR TO HORATIO SWEETSER, JR., OF SAME PLACE.

PAPER-HANGER'S ROLLER.

SPECIFICATION forming part of Letters Patent No. 290,813, dated December 25, 1883.

Application filed July 17, 1883. (No model.)

To all whom it may concern:

Be it known that I, HORATIO SWEETSER, of the city, county, and State of New York, have invented a new and useful Improvement in 5 Paper-Hangers' Rollers; and the following is declared to be a full and exact description of the same.

Paper-hangers' rollers usually consist of a handle to which is secured a wire bail or 10 metal frame, between the ends of which is hung a wooden roller covered with felt or sheep-skin. These rollers are used to press the paper upon the wall and smooth it as it is hung.

15 My invention relates to rollers of this class; and the object of the same is to produce a superior article—one that can be adjusted for wear and can easily be taken apart and packed in a small space for transportation among the 20 other tools of the workman.

I employ a felt-covered wooden roller, (preferably hollow.) The ends of this roller have upon their faces disks or plates of metal secured by nails or screws, and pointed adjustable screw-axles are inserted in the center of 25 these plates for the axis of the roller. These screw-axles are clamped with a nut or screw-plate. The metal frame for the roller is secured to the handle by a screw-rod passing 30 through said handle, one end of which rod is made as a ring for hanging up the roller, and said ring acts as a clamp to hold the handle and frame together when the parts are screwed to place. These rollers can be easily and 35 quickly taken apart and packed in a small space.

In the drawings, Figure 1 is a sectional elevation of the roller complete. Fig. 2 is an elevation of the end of the roller and a vertical section through part of the handle.

40 The roller *a* is of wood, (preferably hollow,) and it is covered with felt of any desired thickness.

To each end of the roller is secured a disk 45 or plate of metal, *b*, preferably by screws. The roller is supported or hung in the metal frame *c* by the adjustable screw-axles *d d'*, which are carried in the plates *b*, and I provide clamping nuts or plates *e e'* upon the 50 axles *d d'*, so as to hold the axles securely in place after the roller is placed in the frame *c* and adjusted. The ends of the axles are pointed, so as to bear evenly and accurately in the depressions in the frame *c*. The wooden han-

dle *f* has a hole through its length for the 55 screw-rod *g*, one end of which rod is made with a ring, *1*, for hanging the roller upon a hook, when desired. The other end of the rod *g* is made with a screw-thread, *2*, for securing the handle *f* and frame *c* together. 60 The end of the handle *f* and the ferrule *3* upon the same are notched at *4* for the reception of the frame *c*, and the handle *f* is thus kept from turning upon the rod *g*, both when the parts are secured together and when the roller 65 is in use.

I prefer to make a small hole in the screw-axles *d d'*, between the point and the nuts or plates *e e'*, so that a nail or sharp instrument can be inserted to turn the axles in adjusting 70 the same or when taking the roller out of the frame *c*.

In my improved roller the adjustability of the screw-axles *d d'* allows any slack produced from wear to be taken up very quickly, and 75 provides a means of keeping the roller steady yet free to turn.

I do not limit myself to the use of these improvements upon paper-hangers' rollers alone, as there are other forms and kinds of rollers 80 to which they are applicable.

I claim as my invention—

1. In a paper-hanger's roller, the combination, with a handle and frame for supporting the roller, of the roller *a*, end plates, *b b'*, adjustable screw-axles *d d'*, and the nuts or plates *e e'* upon said axles, substantially as set forth.

2. In a paper-hanger's roller, the combination, with a roller, its axles, and supporting frame, of the handle *f*, screw-rod *g*, the loop or ring *1* upon the screw-rod, and notch at *4* upon the handle, substantially as set forth.

3. In a paper-hanger's roller, the combination, with a roller, its axles, and supporting frame, of a handle, and a screw-rod passing through the handle and securing the same to the frame, as set forth.

4. A roller for paper-hangers' use, composed of the roller *a*, disks *b b'*, adjustable screw-axles *d d'*, nuts *e e'*, frame *c*, handle *f*, and screw-rod *g*, substantially as set forth.

Signed by me this 14th day of July, A. D. 1883.

HORATIO SWEETSER.
